CONTACT LENS STEAMER UNIT OR THE LIKE

George F. Sitterle, Jacksonville, Fla., assignor to Frontier Contact Lenses of Florida, Inc., Jacksonville, Fla.

Filed Feb. 21, 1973, Ser. No. 334,265

Term of patent 14 years

Int. Cl. D15—99

U.S. Cl. D49—11

FIG. 1

FIG. 4

FIG. 2

FIG. 5

FIG. 3

FIG. 6

FIG. 1 is a top plan view of the contact lens steamer unit showing my new design, with the removable cover shown in its closed position and with the cord shown broken away to indicate indeterminate length;

FIG. 2 is a front elevational view thereof, the rear elevational view being identical, the side elevational views being identical except for the upwardly protruding hand hold from the cover which would be the same as shown in FIG. 6;

FIG. 3 is a bottom view thereof, with the cord shown fragmentarily for ease of illustration;

FIG. 4 is a top plan view similar to FIG. 1 but with the inner portion of the cover rotated 90° to vertically align one pair of openings respectively on the inner and outer portions of the cover and the cord shown fragmentarily for ease of illustration;

FIG. 5 is a top plan view with the two openings of the inner portion being aligned with the two openings of the

outer portion of the cover member and the cord shown fragmentarily for ease of illustration; and

FIG. 6 is a sectional view taken along line 6—6 of FIG. 2.

I claim:

The ornamental design for contact lens steamer unit or the like, substantially as shown and described.
